UNITED STATES PATENT OFFICE.

FREDERICK SKELTON, OF BURLINGTON, AND WILLIAM PICKARD, OF BARTONVILLE,
ONTARIO, CANADA; SAID PICKARD ASSIGNOR TO SAID SKELTON.

D-HANDLE

1,240,502.

Specification of Letters Patent. Patented Sept. 18, 1917.

Application filed January 22, 1917. Serial No. 143,627.

To all whom it may concern:

Be it known that we, FREDERICK SKELTON and WILLIAM PICKARD, subjects of the King of Great Britain, residing at Burlington and Bartonville, respectively, in the Province of Ontario and Dominion of Canada, have invented certain new and useful Improvements in D-Handles, of which the following is a full, clear, and exact description.

This invention relates to D-handles for shovels, spades and other tools, and more particularly to wooden handles which are formed by inserting a grip-bar between the ends of a fork or yoke formed by bifurcating and spreading the upper portion of a wooden haft or stem to which the tool is secured.

The objects of the invention are to provide a wooden handle of this character that is reinforced by metallic parts which are arranged to protect the wooden portions of the handle from injury to prevent splitting or cracking of the wood, and to eliminate the wear such as would be occasioned by the friction between the wood and harder objects.

With these and other objects in view, the invention consists of the constructions and combinations which will be hereinafter set forth and particularly pointed out in the appended claims.

In the accompanying drawings:

Figure 1 is an elevation partially in section of a handle constructed in accordance with the principles of the invention; Fig. 2 is an end view thereof; and

Fig. 3 is a sectional detail.

In the drawings, the wooden haft or stem to which the metallic shovel, spade or other tool, is secured, is only partially shown, and is indicated 1. The upper end of this wooden haft or stem is bifurcated to provide two arms 2 and 3, which are spread and bent to provide a fork or yoke. A rivet 4 is preferably passed through the stem just below the beginning of the bifurcation and transversely thereto to prevent it from splitting.

Inserted between the spaced upper ends of the two arms 2 and 3, is a grip-bar 5, which is cylindrical in shape. Each end of this grip-bar is of reduced diameter as at 5', and is fitted within a ring 6 forming an integral part of a cup-shaped cap 7. However, the closed end of the cap 7, instead of being spherical in shape, is preferably of a cylindrical contour, the curvature corresponding

to the curvature of the outer surface of the arms 2 and 3, which is similar to the curvature of the wooden stem or haft 1. Each of the caps 7 is slotted at the bottom to provide segmental-shaped openings through which the arms 2 and 3 pass, the ends of the arms being covered and concealed by the caps 7 when the caps are mounted in place thereon. Metallic reinforcing strips 8 are secured to the outer surfaces of the arms 2 and 3, which strips are curved to fit the outer surfaces of the arms and are fastened thereto adjacent their lower ends by rivets 9. The upper portions of these strips project into the caps 7 and fit snugly against the inner cylindrical shaped wall of the cap. The upper end 10 of each strip is bent over the end of an arm and is held in position by the caps which bear against it. A rod or rivet 11 passes through the grip-bar 4, and also through the ends of the arms 2 and 3, the reinforcing strips 8 and the caps 7, and rigidly unites these parts together. The rivet 11 will also hold the caps 7 in close engagement with the reinforcing strips 8, and its bent over portion 10, so that these parts will be rigidly held together.

The reinforcing strip 8 extends sufficiently down the arms 2 and 3 to prevent the arm from splitting or cracking under the stresses and strains to which the handle is subjected, while the tool is being used. These strips will also serve to protect the wooden arms 2 and 3 should the tool be subjected to rough usage and will also serve to prevent undue wear of the arms which would be occasioned by the arms rubbing against a harder object such as the sides of a wagon or the like. It will, therefore, be seen that the construction described provides a rigid and durable handle which is of cheap construction and one which can be readily manufactured.

We claim:

1. A D-handle for tools comprising a wooden haft having a bifurcated upper end providing diverging arms, a grip-bar between the upper ends of the arms, caps mounted on the upper ends of said arms engaging said grip-bar, reinforcing strips secured to said arms, the upper ends of said strips being concealed within said caps, and a pin passing through said arms, grip-bar, caps and reinforcing strips.

2. A D-handle for tools comprising a

wooden haft having a bifurcated upper end providing diverging arms, a grip-bar between the upper ends of said arms, caps fitting over the ends of said grip-bar, said caps having openings therein through which said arms pass, reinforcing strips secured to said arms having their upper ends projecting through said opening in said caps, and a pin passing through said arms, grip-bar, caps and reinforcing strips.

3. A D-handle for tools comprising a wooden haft having a bifurcated upper end providing diverging arms, a grip-bar between the upper ends of said arms, caps fitting over the ends of said grip-bar, reinforcing strips on said arms secured to the outer surface of said arms, said reinforcing strips having their upper ends bent over the upper edge of said arms, said caps having openings therein through which said arms and reinforcing strips pass, and a pin passing through said arms, grip-bar, caps and reinforcing strips.

4. A D-handle for tools comprising a wooden haft having a bifurcated upper end providing diverging arms having curved outer surfaces, a grip-bar between the upper ends of said arms, caps fitting over the ends of said grip-bar, said caps having their ends of generally cylindrical shape, reinforcing strips on said arms secured to the outer

surface of said arms, said caps having segmental-shaped openings therein through which said arms and reinforcing strips pass, the portion of said reinforcing strips within said caps engaging therewith, and a pin passing through said arms, grip-bar, caps and reinforcing strips.

5. A D-handle for tools comprising a wooden haft having a bifurcated upper end providing diverging arms having curved outer surfaces, a grip-bar between the upper ends of said arms, caps fitting over the ends of said grip-bar, said caps having their ends of generally cylindrical shape, reinforcing strips on said arms secured to the outer surface of said arms, said reinforcing strips having their upper ends bent over the upper edge of said arms, said caps having segmental-shaped openings therein through which said arms and reinforcing strips pass, the portion of said reinforcing strips within said caps engaging therewith, and a pin passing through said arms, grip-bar, caps and reinforcing strips.

In witness whereof, we hereunto subscribe our signatures.

FREDERICK SKELTON.
WILLIAM PICKARD.
